UNITED STATES PATENT OFFICE.

EDWIN M. FITZGERALD, OF NEW YORK, N. Y.

ADVERTISING APPARATUS.

SPECIFICATION forming part of Letters Patent No. 251,855, dated January 3, 1882.

Application filed May 27, 1881. (No model.)

To all whom it may concern:

Be it known that I, EDWIN M. FITZGERALD, of the city, county, and State of New York, have invented a new and Improved Advertising Apparatus, of which the following is a specification.

Figure 1, Sheet 1, is a front elevation of my improvement, partly in section. Fig. 2, Sheet 1, is a sectional plan view of the same, taken 10 through the line *z z*, Fig. 1. Fig. 3, Sheet 2, is a sectional side elevation of the same, taken through the line *x x*, Fig. 1. Fig. 4, Sheet 2, is a sectional side elevation of the same, taken 15 through the line *y y*, Fig. 1. Fig. 5, Sheet 2, is a sectional elevation of a part of the operating mechanism.

Similar letters of reference indicate corresponding parts.

The object of this invention is to secure the 20 automatic changing of a series of advertisements at regular intervals.

The invention consists in an advertising apparatus formed by combining with a clock-work a series of rollers carrying an endless band, and a spring-driven chain of gear-wheels, 25 a cam, a cam-operated lever, a weighted trip-lever, a set of catch-arms and their shaft, a gear-wheel having a catch-pin, a single-toothed ratchet-wheel, and a shaft, whereby the band 30 will be moved automatically through fixed distances at regular intervals, as will be herein-after fully described.

In the accompanying drawings, A represents the case or frame of the apparatus, to suitable 35 supports in the upper part of which is attached a clock-work, B. The clock-work B is made in the ordinary manner, except that one of the shafts is provided with a cam, C. I prefer to attach the cam C to a shaft revolving once a 40 minute; but it can be attached to a shaft having a faster or a slower movement, as may be required. The clock-work B is designed to be provided with a dial, D, a minute-hand, E, and an hour-hand, F, in the ordinary manner.

G is a lever, which is pivoted to the frame 45 of the clock-work B, or some other suitable support, in such a position that the inner end of the said lever will be struck and operated by the cam C at each revolution of the cam.

50 The outer arm of the lever G passes beneath the outer arm of a lever, H, which is pivoted to the frame I. The inner arm of the lever H

is bent to one side in such a position that when the outer arm of the said lever H is raised the end of the inner arm will be moved inward, so 55 as to receive a pin, J, attached to a wheel, K, pivoted to the frame I, and thus stop the movement of the said wheel K. The outer end of the lever H is made heavy, or has a weight, L, attached to it, so that the said outer end, when 60 released by the descent of the outer arm of the lever G, will drop and withdraw the inner end of the said lever from the pin J, allowing the wheel K to revolve.

To the outer part of the frame I is pivoted 65 a shaft, M, to which is rigidly attached an arm, N. The arm N projects upward, is bent inward, is then bent to one side, and its end passes across the upper side of the weighted arm of the lever H, so that the arm N will be 70 raised by raising the said weighted arm of the lever H.

To one end of the shaft M is rigidly attached 75 an arm, O, which projects inward, and has its inner end bent downward into hook form to engage with the pin J of the wheel K, and thus stop the said wheel. To the other end of the shaft M is rigidly attached an arm, P, which projects inward, and has a hook formed upon 80 its inner end to engage with the single-toothed ratchet-wheel Q, attached to the shaft R. The catch-arm P is made heavy, so that when the trip-arm N is released by the descent of the weighted arm of the lever H the weight of the 85 said catch-arm P will turn the shaft M and lower the catch-arm O into position to engage with the pin J of the wheel K and lower the said catch-arm P upon the ratchet-wheel Q, ready 90 to engage with the tooth of the said ratchet-wheel. The shaft R is connected by a chain 95 of gear-wheels, S, with the stop-and trip-wheel K, and with a coiled spring, T, connected with the frame I. The shaft of the spring T is connected with its gear-wheel by a pawl and ratchet in the ordinary manner, so that the said shaft 95 can be turned to wind up the spring T without turning the gear-wheels S. The shaft R revolves in bearings in the case or frame A, and is extended beneath the clock-work B.

To the extended part of the shaft R is attached 100 a roller or drum, U, around which passes an endless apron or band, V. The band V also passes around five drums or rollers, W, more or less, as the desired length of the band V may

require. Upon the band V is designed to be printed or otherwise formed a series of advertisements, which are designed to be exhibited, one at a time and successively, through a glass plate, X, secured in an opening in the lower part 5 of the front of the case A.

With this construction, as the cam C comes in contact with the lever G it raises the outer end of the said lever G and the weighted end 10 of the lever H, bringing the inner end of the said lever H into position to receive the pin J of the wheel K. The upward movement of the lever H raises the catch-arms O and P out 15 of gear and holds the said arms raised until the spring T has turned the wheel K so far as to bring the pin J in contact with the end of the lever H and has turned the shaft R so far that the hook of the catch-arm P has been carried past the tooth of the ratchet-wheel Q. As 20 the lever G is released from the cam C the weighted end of the lever H withdraws the inner end of the said lever from the pin J and allows the wheel K and the shaft R to be revolved by the spring T, the end of the catch-

arm P riding upon the ratchet-wheel Q, ready 25 to engage with the tooth of the said ratchet-wheel Q when the shaft R has completed a revolution. The roller U, that drives the band V, is so arranged in size that one revolution of the shaft R and roller U will move the band V 30 sufficiently far to carry one advertisement out of sight and bring the next one into view.

Having thus fully described my invention, I claim as new and desire to secure by Letters Patent—

An advertising apparatus constructed substantially as herein shown and described, consisting of the clock-work B, the series of rollers U W, carrying an endless band, V, the spring-driven chain of gear-wheels S, the cam C, the lever G, the weighted catch-lever H, the arm N, the trip-arms O P and their shaft M, the gear-wheel K, having pin J, and the single-toothed ratchet-wheel Q, as set forth.

EDWIN MICHAEL FITZGERALD.
